DRAIN FOR WINDOWS

Fred J. Westrope, Detroit, Mich., assignor to The Murray Corporation of America, a corporation of Delaware

Application October 18, 1934, Serial No. 748,779

12 Claims. (Cl. 296—44)

My invention relates to windows and particularly to a rain-proof construction therefor which prevents the entrance of moisture into a vehicle when the window is mounted in sloping relation to the vertical.

In view of the stream line construction of the present vehicles, it has become necessary to mount certain windows thereof at a substantial angle to the vertical. For this reason the present type of window construction is unsatisfactory since any moisture entering around the window will drop into the vehicle rather than flow down along the window into a trough as occurred when the window was vertical or substantially vertically disposed.

In practicing my present invention, I have provided a frame and trough construction for a window which prevents any water which may enter around the window from escaping to the inside of the vehicle body by directing it into a trough which conducts the water to a point outside of the body. The structure has been materially simplified by employing a U-shaped Z-member which outlines the window and forms a portion of the receptacle thereof. The channel for guiding the window is likewise of U-shape secured directly to the U-shaped Z-member. A window receiving receptacle embodying a water receiving trough is formed on the U-shaped Z-member by a sheet of material which is secured to the lower portion of the extending ends of the member. The sheet material forms the outer side and the bottom of the receptacle and extends only part way up the inner side to provide a ledge for a seat shelf. A window regulating mechanism is secured to a metal panel which forms the complete window receiving receptacle when secured to the inner side of the Z-member above the ledge portion of the sheet material. The metal panel has a rubber sealing element at its lower end which extends into and engages the surface of the sheet material to form a seal therewith. End caps are provided for closing the ends of the metal sheet which is secured to the Z-shaped member. The window regulator panel has the side edges flanged and bent outwardly to project within the end caps for collecting any water passing by the window and conducting it into the trough formed by the U bent panel and the end cap from which it is conducted by a suitable conduit to the exterior of the body. The window thus constructed may be disposed at a very steep angle and assurance is had that any water passing around the window will not drip

within the vehicle but will be caught in the side channels and directed into the receptacle.

Accordingly, the main objects of my invention are; to provide a frame and receptacle for a window which is rain proof when mounted at a substantial angle to the vertical; to form a slanting rain proof window receiving receptacle and frame from a U-shaped Z-member upon which the window and receptacle are supported; to provide a U-shaped Z-member for encompassing a window and supporting a receptacle at its lower end; to provide a U-shaped frame element having a box like receptacle at its lower end formed to have outwardly projecting channels along the side which projects within the receptacle; to provide a frame and receptacle for a window with side projecting channels which extend within the receptacle; to provide a removable metal panel as a portion of the receptacle which has a sealing element for sealing the panel with a side portion of the receptacle; to provide extending flanges on the removable panel to form channels on the sides of the receptacle; to mount a window regulating mechanism on the removable panel; and in general to provide a frame and a receptacle for a window which may be tilted at a material angle relative to the vertical and sealed to prevent water leaking thereby, all of which is simple in construction, positive in operation and economical of manufacture.

Other objects and features of novelty of my invention will be specifically pointed out or will become apparent when referring, for a better understanding of my invention, to the following description taken in conjunction with the accompanying drawings, wherein:

Figure 1 is a broken view, partly in sections and partly in elevation, of a window frame and receptacle embodying features of my invention.

Fig. 2 is an enlarged broken sectional view of the structure illustrated in Fig. 1, taken on the line 2—2 thereof.

Fig. 3 is an enlarged sectional view of the structure illustrated in Fig. 1, taken on the line 3—3 thereof, and

Fig. 4 is a reduced sectional view of the structure illustrated in Fig. 2, taken on the line 4—4 thereof.

Referring to the figures, I have illustrated an automobile body 5 constructed from a metal panel 6 having a window opening 7 therein in which a frame and receptacle for a window 8 embodying my invention, is supported. From Fig. 3 it will be noted that the window frame and receptacle

is tilted at a substantial angle to the vertical and is supported directly on the panel 6.

The inner edge of the opening 7 of the body 5 is provided with an L-shaped flange 9 forming a side and bottom of a glass run channel. A Z-shaped member 11 of inverted U-form mates with the L-shaped flange 9 at the top and sides of the window opening 7 and extends downwardly below the opening for a distance at least equal to the height of the window 8. The Z-member is welded directly to the L-shaped flange 9 with the free ends extending therebeyond. On the facing surfaces of the extending portions of the Z-member glass run channel strips 19 are secured, preferably by welding, in aligned relation with the L-shaped flange 9 about the window opening 7.

A U-shaped panel 10 is then secured to the flanges of the Z-member, the panel comprising a side 12, a bottom 13 and a short side 14 having a projecting flange 15 thereon braced by embossed portions 16 for supporting one end of a seat shelf 17. The U-shaped panel element 10 extends laterally beyond the web of the Z-member, at 18, as illustrated in Fig. 2. The panel 10 is welded to the flange of the Z-member 11 to form a box section therewith with the bottom 13 disposed slightly below the ends of the Z-member so that the water, collecting on the bottom 13, may pass thereunder.

End cap 21 encloses the ends of the sides 12 and 14 and the bottom 13 to form a receptacle therewith. At least one of the caps 21 is provided with an outlet conduit 22 which is welded, brazed, soldered or otherwise secured thereto. The upper end of the side 12 is provided with a projecting flange 23 having a rubber element 24 thereof which engages a flange 25 on the lower edge of the body panel 6 to form a seal therewith.

A window regulator supporting panel 26 is constructed to extend across the Z-member and is provided with a flange 27 at each side edge which projects outwardly of the body to form a trough with the web of the Z-member, the lower end of which projects within the cap 21. The inwardly disposed flanges of the Z-member have a plurality of nuts 28 secured thereto in which suitable screws 29 are disposed to retain the panel 26 on the Z-member. The upper edge of the panel 26 is of arcuate shape, providing the extending ends 31, as illustrated in Figs. 1 and 3, so as to follow the contour of the lower edge of the window opening. The lower end of the panel is deflected inwardly at 32 and is provided with a rubber sealing element 33 which engages the inner surface of the side 14 to form a seal therewith. A suitable window regulating mechanism 34 is mounted on the panel having arms 35 which engage and support the window 8 for upward and downward movement in the channel strip 41 retained by the L-shaped flange 9 and the channels 19. A handle 37 projects from the panel within the body in a position to operate the window mechanism 34. Suitable clips 38 are provided on the panel 26 to receive and support the finished panel 39 thereon.

The glass guide channel strip 41, retained by the L-shaped flange 9 and the channels 19, preferably is made of rubber and has a metal channel strip imbedded therein. The rubber is covered with a felt, or frictionless material to permit the glass to readily slide therein. The metal channel portion provides rigidity and permits the channel strip 41 to be secured at a minimum number of points when retained by the L-shaped

flange 9 and the channels 19. The conduit 22 is connected by a hose, or other means, to a point exterior of the body to prevent any of the water from collecting therewith.

In operation, when the window frame and receptacle is mounted on the vehicle at a substantial angle to the vertical, as illustrated in Fig. 3, any water collecting on the window will run into the receptacle between the side 12 and the panel 26. Any water which may leak at the corners 31 and pass around the Z-member 11 will be collected with the flange 27 and conducted into the caps 21 and the bottom 13 of the receptacle 10. All of the water forced around the frame or receptacle will be collected by the bottom 13 and will be conducted exteriorly of the vehicle body and will be prevented from dripping within the body.

While I have described and illustrated but a single embodiment of my invention, it will be apparent to those skilled in the art that various changes, omissions, additions and substitutions may be made therein without departing from the spirit and scope of my invention, as set forth in the accompanying claims.

I claim as my invention:

1. A frame and receptacle for a window including, in combination, a panel having a window opening with the metal at the marginal edge of the opening extending inwardly, a U-shaped element supported on said metal with portions projecting therebelow, a U-shaped member secured to the projecting portions of said element to form a box section structure therewith with the bottom extending below said projecting portions, and end caps sealing the ends of said U-shaped member.

2. A frame and receptacle for a window including, in combination, a panel provided with a window opening, a U-shaped element extending along the top and side of the window opening, and projecting therebelow, a member of U shape forming two sides and a bottom of a receptacle and secured to said projecting member, an end cap sealing the two sides and bottom of said member.

3. A frame and receptacle for a window including, in combination, a panel provided with a window opening, an element of angle cross-section extending along the top and sides of the window opening and projecting therebelow, a panel forming the back, the bottom and a portion of the front side of the receptacle and secured to said projecting portions, and a regulator panel securable to said receptacle and projecting portions to complete the side thereof.

4. A frame and receptacle for a window including, in combination, a panel provided with a window opening, an element of angle cross-section and of inverted U form extending along the top and sides of the window opening and projecting therebelow, a panel forming the back, the bottom and a portion of the front side of the receptacle and secured to said projecting portions, a regulator panel securable to said receptacle and projecting portions to complete the front side thereof, the side edges of said panel being flanged and extending beyond said projecting portions to form troughs exteriorly thereof.

5. A frame and receptacle for a window including, in combination, a panel provided with a window opening, an element of angle cross-section extending along the top and sides of the window opening and projecting therebelow, a panel forming the back the bottom and a por-

tion of the front side of the receptacle and secured to said projecting portions, a regulator panel securable to said receptacle and projecting portions to complete the front side thereof, the side edges of said panel being flanged and extending beyond said projecting portions to form troughs exteriorly thereof, and end caps secured to the side edges of said back, bottom and front portions of the first said panel to form closures encompassing said flanges.

6. A frame and receptacle for a window including, in combination, a panel provided with a window opening, an element of angle cross-section preformed in the shape of a U and extending along the top and sides of the window opening and projecting therebelow, a panel forming the back, the bottom and a portion of the front side of the receptacle and secured to said projecting portion, a removable panel securable to said receptacle and projecting portion to form the complete front side thereof, the sides of said panel being flanged and extending beyond said projection to form a trough exteriorly thereof, end caps secured to the side edges of said back, bottom and front portions of the first said panel to form closures encompassing said flanges, and a conductor extending from said receptacle in a position to conduct water therefrom.

7. A frame and receptacle for a window including, in combination, a panel provided with a window opening, a frame element extending along the top and sides of the window opening and projecting therebelow, an element having two sides and a bottom supported on said projecting portions, and a removable panel cooperating with one of said sides in such manner as to conduct water within said receptacle.

8. A frame and receptacle for a window including, in combination, a panel provided with a window opening, a frame element extending along the top and sides of the window opening and projecting therebelow, a U-shaped panel member having one side shorter than the other supported on said projections, and a removable panel mated

with said short side to complete the receptacle.

9. A frame and receptacle for a window including, in combination, a panel provided with a window opening, a frame element extending along the top and sides of the window opening and projecting therebelow, a U-shaped panel member having one side shorter than the other supported on said projections, and a removable panel mated with said short side to complete the receptacle and said removable panel having a sealing means 10 with said short side.

10. A frame and receptacle for a window including, in combination, a panel provided with a window opening, a frame element extending along the top and sides of the window opening and projecting therebelow, a U-shaped panel member having one side shorter than the other supported on said projections, a removable panel mated with said short side to complete the receptacle, and sealing means on said removable panel 15 in sealed engagement with said side.

11. A frame and receptacle for a window including, in combination, a panel provided with a window opening, a frame element extending along the top and sides of the window opening and projecting therebelow, a U-shaped panel member having one side shorter than the other supported on said projections, a removable panel mated with said short side to complete the receptacle, and a window regulating mechanism supported on 20 said removable panel.

12. A frame and receptacle for a window including, in combination, a panel provided with a window opening, a frame element extending along the top and sides of the window opening and projecting therebelow, a U-shaped panel member having one side shorter than the other supported on said projections, a removable panel mated with said short side to complete a receptacle, and sealing means on the longer side in sealed engagement with the panel having the window opening.

FRED J. WESTROPE.
